UNITED STATES PATENT OFFICE.

WILLIS J. PERKINS, OF GRAND RAPIDS, MICHIGAN.

SHINGLE-SAWING MACHINE.

SPECIFICATION forming part of Letters Patent No. 380,346, dated April 3, 1888.

Application filed June 30, 1887. Serial No. 242,938. (No model.)

To all whom it may concern:

Be it known that I, WILLIS J. PERKINS, residing at Grand Rapids, in the county of Kent and State of Michigan, have invented certain new and useful Improvements in Shingle-Sawing Machines, of which the following is a specification, reference being had therein to the accompanying drawings.

This invention relates to shingle sawing machines of the character which have a rotary carriage carrying a plurality of shingle bolts or blocks to the saws which cut the shingles from said blocks.

The object of the invention is to improve the working parts of a machine of the character described; and the invention consists in improvements in the carriage controlling and operating devices; also, in certain improvements in the mechanism for bringing the blocks to position preparatory to sawing; also, in improved constructions and combinations for delivering the spalt and the sawdust from the machine; also, in many other details of construction and combinations of parts, herein-after described.

Figure 1 is a perspective view of my rotary machine, illustrating generally the various parts of the machine in their relation to each other. Fig. 2 is a side elevation of the machine, some parts being omitted for clearness of illustration. Fig. 3 is another side view of the machine about at a right angle to the view Fig. 2, parts being broken away for clearness of illustration. Fig. 4 is a top plan view of the machine, parts being broken away and parts being omitted for clearness of illustration. Fig. 5 is a plan view with the rotating table or carrier removed and with both saws and their operating mechanism omitted. Fig. 6 is an elevation of one of the tilt-tables and part of its operating mechanism attached to a broken section of the frame. Fig. 7 is an elevation of the same tilt-table, taken about at a right angle from Fig. 6, the tilting mechanism being omitted. Fig. 8 shows details in perspective of the tilt-table and its connections, hereinafter referred to. Fig. 8^a is a vertical section of a part of the tilting mechanism of one of the tilt-tables. Fig. 9 is a perspective view of some of the various parts which form the automatic shifting mechanism of one of the tilt-tables, and Fig. 11 shows further de-

tails of the same. Fig. 10 is a perspective view of one of the saw-shields. Fig. 12 is a perspective of the extensible lever for lifting 55 the carriage-wheel and shaft. Fig. 13 is a vertical section of one of the saw-arbors and its lower bearing, the upper bearing and part of the arbor being in elevation. Fig. 14 is a plan of the lower bearing-box of the saw-arbor and 60 attachments to said box. Fig. 15 is a detail elevation of part of the tilt-table mechanism, (being in the opposite direction from Fig. 6 and at the other side of standard D.) Fig. 16 is a detail section of the tilt table. 65

The shingle-sawing machine is of that general class which has a rotating table hung to a central vertical axis, the table having a number of receptacles for shingle blocks or bolts, and mechanism for holding the bolts in each 70 receptacle. Beneath the outer edges of the table are horizontal saws supported on vertical arbors, which saws successively cut shingles from the lower surfaces of the same blocks. There are also mechanisms for adjusting the 75 blocks to such position that each block shall present just enough of its substance below the plane of the saw to produce a perfect shingle.

In the present machine there are ten receptacles for shingle-bolts in the revolving table, 80 two saws on vertical arbors, and a tilt-table for each saw. Consequently with ten blocks in the table twenty shingles will be sawed with each revolution of the bolt-carrying table; but the number of saws and bolt-receptacles may 85 be increased.

It will be understood that in the present machine all matters relating to the saws, the tilt-tables, and the shingle-supporting ways are duplicated at each side of the machine, excepting (as it is intended that one man shall supervise the whole machine) that devices for throwing one of the tilt-tables out of normal position must cross the machine while the other is at the hand of the operator, and the same is true 95 of the spalt-droppers.

The various parts will generally be described in the singular number in this specification, as with this explanation there will be little difficulty in locating such parts as are duplicated.

The numeral 1 indicates the central shaft of the machine, which runs in bearings 2 and 3 in the main frame A of the machine. The ro-

tary carriage 5 is supported by a spider, 6, attached to the upper portion of the central shaft, 1. The rotary carriage 5 has receptacles 7 for shingle-bolts, each receptacle or frame 5 having a dog, 8, which is forced by a spring, 9, against the shingle-bolt. The spring 9 bears against a shoulder, 10, (see Fig. 4,) on the rotary carriage, and also against a set-nut, 11, on the draw-rod 12, which is pivotally connected with the dog 8 at the end of bent arm 13. The inner end of rod 12 bears an anti-friction roll, 14, which rides against a cam, 15, on the main frame at such point in the revolution of the rotary carriage as it is desired to 15 loosen the dog from the shingle-bolt. By having the track in the center and operating the dog therefrom I have a short run of the roller on the end of the dogging-rod against the track, and the cam which operates the dogging-rod is out of the way of the man who operates the machine—important advantages in machines of this class.

It will be understood that the shingle-bolt will be undogged and permitted to drop as 25 much as the thickness of a shingle when approaching each saw. Consequently in the present machine there will be two cams, 15, while the dogs and connections will equal in number the receptacles for shingle-bolts—that is, ten 30 in this machine. For the guidance and support of the inner ends of the rods 12, there is a link, 16, pivoted to the rotary carriage 5 and to the inner ends of said rods 12. The cam-surfaces of cams 15 are so formed as to undog 35 the bolts at the time they are on the adjustable ways, hereinafter described. The movement of the dogs is toward the center of the machine, and the pressure of the springs and cams is in radial direction.

40 Each bolt-receptacle 7 has two bearing-pieces or pushing-blocks, 17, which are preferably of wood and vertically adjustable between ribs at the rear of the box or receptacle 7. These ribs, in connection with blocks 17, force the shingle-bolts toward the saws during the rotation of the table. The dogs 8 are guided in ways 18, so that they will remain parallel with the inner holding-dogs, 19, of receptacles 7 and at a right angle to the front 45 faces of the bearing-pieces 17 in the receptacles 7.

Beneath the rotary table 5, at each side of the machine, are tracks 20, having an even upper surface, and when the shingle-bolt is 50 undogged it falls upon and is supported by these tracks or ways 20, being forced along the ways in the direction of rotation of the carriage by the pressure of block 17. A section of this way is movable, for the purpose of 55 dropping a spalt or refuse block, as will be hereinafter explained. At the ends of the ways 20 toward the saws are tilt-tables 21. The purpose of these tilt-tables is to drop one 60 end of the shingle-bolt more than the other, so that the shingle sawed from the block shall be wedge-shaped.

The central shaft, 1, which supports the ro-

tary carriage, serves also as a means for lifting the same by means of the lever *a*, pivoted to the standards *b* on the central bar, *B*, of the frame which supports the bearing-box 2. The lever *a* is in sections, the outer section, *c*, sliding on the section *a* and being attached thereto by loops *d* *e*, thus forming an extensible or telescopic lever. (See Fig. 12.) The outer 75 end of the lever is normally held up by a swinging piece, *f*, pivoted to the upper part of the frame at *i* and having hooks or offsets *g* and *h* at its lower end. The lever rests on offset *g* when out of operative position; but when 80 pressed down it may be held down by swinging the projection *h* over it. The inner end of the lever *a* turns up under collar 1', secured firmly on the central shaft, 1, and when the outer end of the lever is pressed down this 85 shaft, its spider 6, and the carriage 5 will be lifted far enough to permit the adjustment or removal of the saws from their arbors. The carriage 5 has an external gear, 30, and is driven by a pinion, 31, engaging therewith. 90 (See Fig. 4.) The pinion 31 is on upright shaft 32, supported in bearings 33 34 on the main frame. A belt-pulley, 35, on shaft 32 has a belt, *x*, passing round pulley 36 on shaft 37, which shaft is supported in bearings and 95 has a pulley, 38, connected by belt *y* with pulley 39 on one of the saw-arbors, the belt *y* straddling the central shaft, 1, of the machine.

The belt *x* is controlled by idler-pulley 40, mounted on one end of three-armed lever 41, 100 which is pivoted at 42 to the frame of the machine, and has an arm, 43, bearing a brake-shoe, which can be swung into contact with the rim of pulley 35 at the same time idler 40 is swung away from belt *x*. The third arm, 44, 105 of the three-armed lever has a draw-rod, 45, attached, which rod is pivotally connected at 46 to the hand-lever 47. The lever 47 has its fulcrum near the bottom of the frame and may be swung into a notch, 48, in an arm of the 110 frame. When lever 47 rests in the notch 48, the idler 40 is swung away from belt *x* and the brake-shoe is thrown into contact with the pulley 35, thus stopping the motion of that pulley, and hence that of the carriage 5, while 115 the movement of saws is not affected. The tilt-tables 21 are made to perform the usual office of such tables, which is to permit the shingle-bolts to drop below the plane of the saw at one end enough to sever the thickness 120 of a shingle-butt and at the other end the thickness of a shingle-point.

In rotary machines having two saws it is customary to have one tilt-table set to make butts on the outward end of the shingle-bolt 125 while the opposite table in normal position makes the butt off of the inner end of bolt, thereby cutting the thick end of the shingle alternately from opposite ends of the bolt and avoiding the necessity of tilting the tables except for the following reasons: A bolt when placed in the machine may be wedge-shaped, and if sawed alternately butts and points there would be a large spalt left that would be still 130

a wedge; but if several shingles were taken off in succession one way it would square the bolt up or make its opposite faces parallel, and several more shingles be cut from it.

5 Again, a knot in a shingle-butt would classify the shingle into a lower and cheaper grade, while the same knot in the point would not be of material detriment to it.

I arrange my tilt-tables to move when desired, so as to lower either end of the bolt carried in any one of the receptacles 7 abnormally, but to return to normal position in time to receive the next succeeding bolt.

The table 21 has a post, 50, attached to its lower surface. (See Figs. 6, 7, and 8.) The post 50 is forked at 51, and the arm 52 is also secured to the table by a screw or in other suitable manner. The post 50 has a cylindrical section, 53, which receives a collar, 54, having a spherical outer surface. The cylindrical section 53 is free to slide in this collar 54. The collar 54 has its outer bearing in a box, 55, (on the frame,) having a semispherical seat, the cap 56 of said box having a similar seat. The box 55 and its cap thus hold the post 50 in such manner that it may have a universal rocking motion in the bearing and may be raised or lowered with respect to the bearing.

30 The table 21 has flanges 60 at its sides, each flange having an inclined lower surface. The inclines correspond with the inclined faces of wedges 62, these wedges being connected by bar 63, having a projection, 64. A set screw, 65, bearing in arm 66 of table 21, engages a screw-thread in projection 64, so that the turning of the set screw will move the wedges 62 transversely with reference to the table 21. The lower faces of wedges 62 are 40 grooved and supported on cups 70, which have splines 71 across their faces and are held up, as will be hereinafter described. The splines 71 fit in the grooves in the lower faces of the wedges. As the cups 70 are fixed against 45 sidewise movement, it will appear that the turning of the set-screw 65 will move the wedges 62 lengthwise, and thus raise or lower the table 21 with reference to the cups 70. The cups 70 are hollow and receive in their cavities the upper ends of the hollow screw-sleeves 72. These sleeves 72 are screw-threaded and may be screwed up or down in the platform C of the main frame and locked by jam-nuts 720. The risers 74 are preferably rods passing 50 through the sleeves 72 and having their upper ends seated in the hollows of cups 70 inside the sleeves 72. The rods or risers 74 are screw-threaded at their lower ends and pass through pivotal nuts 75, which are journaled 55 in the lever or walking-beam 76. Set-nuts 77 serve to secure the risers in any desired relation to the pivotal nuts 75. The walking-beam 76 is pivoted to standard D of the main frame.

From the above-described construction it 55 will be apparent that the sleeves 72 may be set at such a height as to limit the downward movement of cups 70. They are set at such

height as to permit the cups 70, when not otherwise supported, to fall far enough to drop the tilt-table the thickness of a shingle-butt of 70 such gage as may be desired. One of the risers 74, however, will at the same time be lifted by the rocking of beam 76 to such a height that it will support the cup 70, and consequently its end of table 21, to such a height 75 that the shingle-bolt at that end will be only far enough below the plane of the saw to make a shingle-point. Thus the sleeves 72 serve to support the ends of the tilt-table from which the shingle-butts are cut, while the risers 74 80 serve as point-supports for the table. The rocking movement of the walking-beam being a predetermined quantity equal to the making of the most tapering shingle desired, the butt and point supports can be so regulated as 85 to produce any taper of shingle desired, a little lost motion being permitted, when desirable, between the upper ends of the risers 74 and cups 70, so that neither adjustment can interfere with the other. One end, 79, of the vi- 90 brating lever or walking-beam 76 rests in a cam-race, 80, in the edge of a disk, 81. This disk is mounted loosely on rock-shaft 82. The action of the cam-race is to raise or depress the end 79 of the lever 76 whenever the disk 95 81 is made to rotate a partial revolution. The mechanism by which intermitting rotation of disk 81 may be caused is as follows, (see Figs. 1, 9, 10, 11, 15:) The upper face of disk 81 has locking notches 83 and ratchet-teeth 84 100 surrounding its periphery, the notches and teeth being equal in number and opposite the elevations and depressions in the cam-race. A gravity pawl or catch, 85, having a projection, 850, sliding in a guideway, 86, formed in 105 an arm, E, of the frame, falls into one of the notches 83 whenever free to do so. The catch 85 is held up by a cam or curved incline, 87, in the interior of a sector-shaped chamber of wheel 88. Rocker-wheel 88 is firmly secured 110 to rock-shaft 82 and carries a gravity-pawl, 89. The wheel 88 is just above disk 81, so that the pawl 89 will engage the ratchet-teeth 84 when the rocker-wheel vibrates far enough, but will ride over said teeth in the other direction. 115 Cap 90 covers the sector-chamber in rocker-wheel 88 and has a projection, 91, to which a spring, 92, is attached, the other end of said spring being connected to the frame of the machine. 120

The rocker-wheel 88 has a side projection or tooth, 95, and a depending tooth, 94. A weighted lever, 100, pivoted to the standard D of the frame, has a stop, 101, which is in position to engage the tooth 95 on the rocker-wheel when that end of lever 100 is raised, and to engage the tooth 94 when the end of the lever 100 is depressed, and an arm, 102, which passes into the race-cam groove 80. The pull of spring 92 draws the tooth 95 against the stop 101, which is so located with reference to the two pawls carried by rocker-wheel 88 that both pawls are practically inoperative while the lever 100 is in the position shown in Fig. 130

1; but when the weighted end of the lever 100 is lifted the spring rocks the rocker-wheel (and rock-shaft) a little farther until tooth 94 comes against stop 101. This permits pawl 89 to engage a tooth 84, and then when the shaft 82 is rocked, in manner hereinafter explained, the rocker-wheel 88 will move cam-disk 81 with it, and the end of lever 76 will be raised or lowered. As the rocker-wheel 88 moves to the extreme of its movement in the direction of the arrow, Fig. 11, the incline 87 permits the catch 85 to fall, and so lock the cam-disk to arm 86 of the frame, thus securing a solid fastening of the cam-disk for the instant and arresting the momentum. As soon as the rocker-wheel swings in the opposite direction, the incline raises this catch 85, freeing the cam-disk. The weighted lever 100 is connected by rod 103 to handle 104, pivoted to the frame, said rod 103 passing through loop 105 on said lever and having a button 106 just below the loop. The lower end of rod 103 reaches down to a rock-shaft, 107, mounted in bearings and having slotted arm 108, through which the rod 103 passes loosely. Said rod 103 has a nut or button, 2, above the arm 108. The arm is actuated by the depression of rod 103 to rock-shaft 107 against the force of a torsion-spring, 109. The handle 104 can be depressed by the hand of the operator, thus lifting the weighted end of the lever 100 and dropping the other end, so that the rocker-wheel 88 can swing far enough to throw its pawl into engagement with the cam-wheel. Rock-shaft 82 has at its upper end a crank, 110, bearing an anti friction roll, 111. This roll is engaged by an incline, 22, on the carriage-wheel 5 and partially rotates shaft 82 as the bolt carriage or receptacle 7 passes the roll. The operation of this part of the device is as follows: When handle 104 is depressed, its rod 103 lifts the weighted end of lever 100, allowing rocker-wheel tooth 95 to swing over the stop 101 and tooth 94 to engage said stop. The rocker-wheel and cam-disk are then locked together by pawl 89, and when the next cam, 22, on the carriage 5 swings the arm 110 of the rock-shaft 82 the race-cam 81 will be actuated and the tilt-table tilted. The cam-race during this movement holds down the toe 102 of lever 100, so that as soon as the rock-shaft is relieved spring 92 will move the rocker-wheel 88 again to the position to engage pawl 89 with a tooth 84 of cam-disk 81, and the next cam on carriage 5, engaging crank 110 on rock-shaft 82, moves the cam-disk another notch, at the same time relieving the lever 100 from engagement with the race-cam, when the weight will resume control of the lever 100 and the rocker-wheel will be locked in the position where it is left by cam 22 until lever 100 is again tripped. Thus the tripping of said lever 100 causes the rocker-wheel and its connected mechanism to tilt the tilt-table once with the first approaching cam on the carriage 5 and to restore it to normal position with the second one, when the tilt-table will remain stationary until lever 100 is

again tripped. A rod or cord running across the machine from crank-arm 113 connects with the duplicate mechanism actuating the tilt-table on the opposite side of the machine. Thus the operator, by lifting handle 104, serves to throw into operation the mechanism for tilting the tilt-table at one side of the machine, and by a reverse movement of lever or handle 104 he throws the other tilt-table mechanism into operation to tilt the table once and then restore it to normal position. Thus by watching a particular block the operator may take as many abnormal cuts as he desires from said block, the machine restoring itself instantly to normal position for succeeding blocks. The lower end of standard 50 is practically a pendulum, hanging nearly perpendicular to the post D of the frame. To this lower portion, on the face next said post D, there is attached a hinged plate, 120, which may be set out more or less from the face of the post by a set-screw, 121, passing through said standard. As this plate is set out from the standard 50, (being hinged at one side of said standard,) it will assume a greater angle to the face of the standard 50 and post D. A piece, 122, generally a screw with an inclined point, projects from the side of the frame-post D toward the lower end of pendulous piece 50, opposite the plate 120, so that said plate bears against this projection. As the side of table 21 over the arm 52 is heaviest, and as the shingle-bolt is drawn off this side of the tilt-table, the pendulous arm 50 will always have a tendency to retain the plate 120 against the projection 122. Then a shift of the position of the tilt-table will swing this pendulous arm or standard in such manner that the two inclines are kept in contact. The effect of this will be to swing the pendulum a little out of the perpendicular, and as the pendulum is rigidly attached to the tilt-table, the tilt-table will partake of this movement and will have a slight incline in one direction or the other. As each saw is a horizontal plane, any wedge-shaped piece cut from below the carriage, which moves in a parallel plane, must be in some degree of the nature of a conic section. If the tilt-table is shifted in an arc at right angles to the plane of movement of the saw and carriage, this conic section will generally be of unequal thickness at the edges or opposite ends of tilt-table. The mechanism just described enables me to give to the tilt-table such a movement as will overcome this tendency to unevenness by swinging the table "out of true" so much as may be necessary to compensate for the error.

The saws 130 are mounted on vertical arbors 131, which are supported in bearings at each side of the machine. The upper bearing-box, 132, is such as is described as the ball or swivel bearing in my application, No. 204,635, of June 9, 1886. It is thought unnecessary to describe it here further than to say it is such a bearing as permits a universal movement of the upper end of the arbor.

The lower boxes, 133, are of peculiar con-

struction, as will be hereinafter described, to permit of a ready adjustment of the arbor in any direction and to hold the arbor firmly, so that it shall not be permitted to rise and shall be easily and thoroughly lubricated. A strong arm, 134, attached to each box 133, has a loop-connection with bolt 135, which passes through a hole in bracket 136 on the floor of the building. Nuts 137 and 138 on opposite sides of the bracket 136 permit the adjustment of the bolt 135 in such manner as to move the entire machine, it being understood that the boxes 133 are firmly connected to frame A or to projections therefrom. The sawyer's table 140 is in convenient location at the outside of the machine, overhanging the rim of carriage 5. This table is pivoted to brackets 141, so that it can be turned back out of the way. The table is in convenient location to permit a ready grasp of lever 47 or handle 104.

The outer edges of the saws are covered by shields 144, which are of crescent form and are pivotally connected to arms F of the frame, so that the guards may be turned over backward to permit access to the saws. When in position over the saws, the guard 144 is held by a catch, 145, (see Fig. 10,) engaging an arm, 146, projecting from one of the supporting-arms 147 of the shield. It is only necessary to trip the catch in order to turn the shield down away from over the saw. When the sawyer, standing in front of the table 140, drops a new block or bolt into one of the receptacles 7, the bolt falls on table 150, which table consists of a front and rear section, these sections being practically continuations of ways 20. The dog 8 is held back by cam 15 at the time the new block is inserted; but as the carriage rotates the blocks 17 in grooves of receptacles 7 carry the shingle-bolt onto the tilt-table 21, and as soon as the bolt is entirely on the tilt-table (having assumed thereon such position that the thickness of a shingle projects below the plane of the saws) the dog closes on the bolt (by means of spring 9) and holds the bolt firmly toward the center of the rotating carriage during the cutting of the shingle from the bolt. When the block has been sawed into shingles, so that only the spalt or waste remains, it is desirable to drop this spalt from the machine. At the same time it is important that every shingle possible should be cut from the bolt before the spalt is thrown away. It is therefore desirable that the sawyer should be able to cause the spalt to drop at either side of the machine. The ways 20, on which the block rests when undogged, have movable sections 150 151. The section 150 is supported on posts 152 152, which are hinged to the frame at 153 some little distance below the piece 150. The section 151 is supported on posts 154 155, pivoted to the frame at 156 156. A cross-rod, 157, connects the post 155 below its pivot with post 152 above its pivot. (See Figs. 2, 5.) A spring, 158, draws on the upper end of post 152, and hence pulls the section 150 toward the center of the machine, said section 150 having

end bearings against the fixed sections 20 of the ways.

Alongside the carriage-wheel 5, at each side 70 of the machine, there is a curved bar, 160, having an inclined outer end, 161. The inner end, 162, of the curved bar is hinged to the frame-work, as at 164, Fig. 4, and a horizontal piece, 165, is also hinged to the frame at 75 167 below the pivot 164, and connected by an upright, 166, to bar 160, so that the pieces 160 and 165 form practically a small swinging gate or rack hinged to the frame and capable of swinging outward. A rod, 159, connects the 80 outer end of this gate with the upper part of post 152.

A pivoted trip, 170, on the carriage 5 opposite the leading end of each receptacle 7 lies loosely on the rim of the carriage-wheel 85 unless turned into operative position by the hand of the operator. When so turned out, as shown in Fig. 2, the edge of this trip lies in notch 171, and the trip forms a projection radial to the carriage-wheel. In this position, 90 as the carriage rotates, the trip 170 engages the bar 160 and swings said bar and the gate of which it forms a part outward. This draws out the upper end of post 152, and consequently spreads the track-section 150 outward, 95 and as post 152 is connected to post 155 below its pivot, post 155 is rocked to carry the track-section 151 inward. The track-sections 150 151 are thus spread apart far enough for the spalt to fall between them. The movement of 100 the track-sections is toward and from the center of the machine in opening and closing, the track-sections remaining always parallel with each other and with the rim of the revolving carriage. As soon as trip 170 has passed beyond bar 160, its lower surface encounters an incline, 172, which lifts the trip out of notch 171, and when so lifted a stop, 173, serves to turn back the trip 170, so that it lies loosely on top of the carriage-frame. (See Figs. 1, 3.) 110 As the carriage approaches the sawyer at table 140 from his left, if the sawyer sees a spalt should be dropped at once, he turns the trip 170 in front of that spalt into its notch 171 with his left hand, and the spreading of the 115 ways takes place immediately, the spalt being dropped nearly at the side of table 140; but if the sawyer desires to cut one more shingle from the spalt and there be not timber enough to cut two, he must drop the spalt at 120 the opposite side of the machine. This he does by turning the trip 170 into its notch as soon as the trip shall have passed to the right-hand side of his table, and the trip rides in its notch until it comes to the opposite bar, 125 160, when the spalt is dropped, a shingle having been sawed therefrom meanwhile.

It is desirable to saw as many shingles as possible from the spalt, and at the same time it is not advisable to saw the spalt down so 130 thin that it may be carried between the saw and carriage and cause damage to the machine. The dogs, as has been explained, close toward the center of the machine. The tilt

movement is also caused by a swing of the rock-shaft arm in a direction toward the center of the machine, and the spalt-dropper also moves radially. These movements tend 5 to give greater steadiness than if the prime movements of the motors were vertical. The saws cut toward the center of the machine. One sawdust-spout, 180, has an open side in which one of the saws 130 runs, and the spout 10 181 is close to and nearly tangential to this saw, the spout 181 being a continuation of spout 180, but extending straight toward the side of the machine in a direction practically radial. The spout 182 presents its open end 15 toward the periphery of the other saw 130 just inside the inner end of the shingle-bolt when in position for sawing. This spout 182 makes a curve just before its juncture with spout 180, and then joins with said spout 180 20 to form the discharge-spout 181. The sawdust thrown by the saw into the open end of spout 182 is deflected at the curved portion, and is thus glanced along the interior of spout 181 and thrown from the side of the machine. 25 An adjustable piece, 223, can be moved to maintain the same relative distance between the edge of the saw and the spout as the saw wears away.

The upper part or web, C, of the frame consists of branching arms suitably connected by braces and all connected to a central hub forming the upper bearing for the central shaft, 1, of the machine.

Supported on the web C of the frame at opposite sides of the machine are rotary planers 190 just in the rear of the saw in position to plane the lower surface of the shingle-bolt as it comes from the saw, and before the bolt is undogged and dropped on ways 20.

40 It will be understood that in the construction of machines embodying my improvements I do not confine myself to the precise form of mechanism shown; but I propose to avail myself of equivalents in all instances.

45 In the saw-arbor boxes I use a device described in my former application, as has been stated, for the upper or ball bearing. The lower bearing-box is of peculiar construction, as shown more particularly in Figs. 13 and 14.

50 The lower end of shaft 131 runs in a box or casing, 133, which can be partially filled with oil. The lower portion of the arbor has rings 225 integral with it. Said rings fit into corresponding grooves in the box-cap 201. A 55 collar, 200, encircles the shaft 131 and rests on top of the box and cap 201. The bifurcated arm 203 has pivotal bearing in bridge-pot 133 at 205 at one end. A cross-bar, 208, connects its opposite ends and forms a bearing 60 for bridge-screw 207. As the rings 225 are solid with arbor and boxes 201 fit thereon and are held from vertical motion by ring 200 and yoke 205 and screw 207 therefor, said device performs all the functions of a collar, and 65 as it is all within the box the lubrication and expansion of metal are both provided for. The piece 201 is squared and held on each of

its four sides by a set-screw, 202, passing through sides of box 133. The piece 201 can thus be adjusted in any direction by means of 70 the set-screws, thus shifting the base of the arbor to level the saw.

The fork 203 can be pressed down by its pressure bar and nut, so that it will hold boxes 201, and thereby the saw-arbor, firmly against 75 any tendency to rise.

The table 140 has two openings, 220, which serve as gages to denote the position at which the operator must shift the handle 104 to trip the tilt-table. Projections 221 on the opposite 80 side of the carriage serve a similar purpose. The lower part of rim of wheel 5 is supported at opposite sides of the frame by a number of bearing-pieces, 230. These pieces are preferably blocks of wood cut to present the end of 85 the grain toward the wheel which rests on them. The blocks 230 are inserted in troughs 231, and each trough 231 has a lubricating-cup, 232, attached thereto and connected therewith. The cups may be filled with oil, which 90 will pass into the troughs around the bottom of the blocks 230 and will be carried up the pores of the blocks by capillary attraction, so that the surface of these blocks will be constantly lubricated.

95 In the foregoing specifications I have described the best modes now known to me for applying the principle of my invention; but changes, substitutions, and omissions may be made as to the described parts, provided only 100 the essential elements of invention set forth in the following claims are employed.

I do not herein broadly claim a movable section on the track or block support, nor broadly claim supports for the edge of the rotary carrier, the same being claimed in my application, No. 242,815, filed June 28, 1887.

I claim—

1. A shingle-sawing machine having saws mounted on vertical arbors and a rotary bolt-carriage supported on a central vertical shaft, in combination with a lever extending from the outside of the frame to the central shaft, fulcrumed near and having a bearing on said shaft, whereby the shaft and carriage may be 115 lifted to permit access of the saws, substantially as described.

2. The combination, with the rotary carriage and central vertical shaft of a shingle-sawing machine, of a lever formed of sections, 120 the inner section fulcrumed near and engaging the central shaft of the carriage, and the outer section extensible beyond the outer portion of the frame of the machine, substantially as set forth.

3. The combination, with the rotary carriage of a shingle-sawing machine, of a central vertical supporting-shaft, a lever stepped under said shaft and extending outside the frame of the machine, and a swing - piece attached to the frame and adapted to engage said lever and hold it up or down, substantially as described.

125 4. The combination, with the rotating car-

- riage of a shingle-sawing machine, of a dog near the periphery of said carriage, a bent arm pivotally connected at its outer end to said carriage and at its inner end bearing an anti-friction roll, a spring surrounding said arm, having an abutment on the carriage, and an adjustable abutment on the arm, whereby the pressure of the spring may be regulated, and a cam or incline on the frame against which the anti-friction roll has a bearing in the rotation of the carriage, substantially as described.
5. The combination, with the rotary carriage of a shingle-sawing machine, of a dog near the periphery thereof and guided in radial ways in said carriage, an arm connected to said dog and extending inwardly past the stationary dog toward the center of the carriage, a spring pressing said arm and dog inwardly, a cam-surface on the frame in position to press out the said arm during a portion of the revolution of the carriage, and a support for the inner end of said arm, substantially as described.
10. The combination, with the rotating carriage having a rack, of a shaft bearing a pinion engaging said rack, a pulley on said shaft, a counter-shaft toward the opposite side of the machine, having suitable pulleys and belt-connection to the pinion-shaft, a saw-shaft, and a belt-connection from said saw-shaft straddling the central arbor connecting to one of the pulleys on said counter-shaft, as set forth.
15. The combination, with the rotating carriage having a rack, of a shaft bearing a pinion engaging said rack, a pulley on said shaft, a counter-shaft toward the opposite side of the machine, having suitable pulleys and belt-connection to the pinion-shaft, a saw-shaft, and a belt-connection from said saw-shaft straddling the central arbor connecting to one of the pulleys on said counter-shaft, as set forth.
20. The combination, with the rotating carriage having a rack, of a shaft bearing a pinion engaging said rack, a pulley on said shaft, a counter-shaft toward the opposite side of the machine, having suitable pulleys and belt-connection to the pinion-shaft, a saw-shaft, and a belt-connection from said saw-shaft straddling the central arbor connecting to one of the pulleys on said counter-shaft, as set forth.
25. The combination, with the rotating carriage having a rack, of a shaft bearing a pinion engaging said rack, a pulley on said shaft, a counter-shaft toward the opposite side of the machine, having suitable pulleys and belt-connection to the pinion-shaft, a saw-shaft, and a belt-connection from said saw-shaft straddling the central arbor connecting to one of the pulleys on said counter-shaft, as set forth.
30. The combination, with the rotating carriage having a rack, of a shaft bearing a pinion engaging said rack, a pulley on said shaft, a counter-shaft toward the opposite side of the machine, having suitable pulleys and belt-connection to the pinion-shaft, a saw-shaft, and a belt-connection from said saw-shaft straddling the central arbor connecting to one of the pulleys on said counter-shaft, as set forth.
35. In a shingle sawing machine, in combination, a horizontal saw, a tilt-table supported on a universal bearing, a pendent lever connected to said table, means for tilting the table longitudinally, and a shifter for operating the table laterally during the longitudinal movement, whereby the table is tilted longitudinally and laterally at the same time, substantially as described.
40. The combination, with the horizontal saws and rotary carriage of a shingle-sawing machine of the character described, of a tilt-table at each side of the machine, a train of mechanism by which either tilt-table may be tipped by power communicated from the rotary carriage, a handle near the operator's position, and connections, substantially as described, leading from the handle to each tilt-table, whereby the tilt-tables may be separately thrown into operation, as set forth.
45. The combination, with the rotating saws and carriage, of a tilt-table at each side of the machine, a train of mechanism, substantially as described, whereby each tilt-table may be separately actuated from the rotary carriage, a handle pivoted to the frame near the operator's position, a rod connecting said handle to the tilt-controlling catch at one side of the table, and a lever and controlling-catch connected to said rod, whereby the other tilt is actuated by moving the handle in reverse direction, as set forth.
50. The combination, in a shingle-sawing machine, of a tilt-table, an oscillating beam for rocking the same, a rotating cam engaging said beam, a power-driven rocker, and a clutch by which said rocker and cam may be thrown into connection.
55. The tilt-table and its walking-beam, the loosely-mounted cam, the rock-shaft and rocker-wheel fixed thereto, a clutch between the rocker and cam, and a holding-stop by which the rocker is held, so that the clutch cannot come into engagement.
60. The oscillating beam of the tilt-table engaging the race-cam, a rocker-wheel in proximity to the race-cam, having two stops thereon, and a detent in position to swing in front of one or the other of the stops of the rocker, the specified elements in combination, substantially as set forth.
65. The combination, with the tilt-table and its rocking beam, of the race-cam engaging said beam, the rock-shaft on which said cam is loosely mounted, having a rocker-wheel thereon provided with a series of stops, a clutch between the rocker-wheel and cam, and a plurality of detents in position to engage the stops on the rocker-wheel, and a handle on the frame near the operator's position by which said detents are operated, substantially as described.
70. The combination, with the tilt-table and its rocking beam, of the race-cam engaging said beam, the rock-shaft on which said cam is loosely mounted, having a rocker-wheel thereon provided with a series of stops, a clutch between the rocker-wheel and cam, and a plurality of detents in position to engage the stops on the rocker-wheel, and a handle on the frame near the operator's position by which said detents are operated, substantially as described.
75. The combination, with the tilt-table and its rocking beam, of the race-cam engaging said beam, the rock-shaft on which said cam is loosely mounted, having a rocker-wheel thereon provided with a series of stops, a clutch between the rocker-wheel and cam, and a plurality of detents in position to engage the stops on the rocker-wheel, and a handle on the frame near the operator's position by which said detents are operated, substantially as described.
80. The combination, with the tilt-table and its rocking beam, of the race-cam engaging said beam, the rock-shaft on which said cam is loosely mounted, having a rocker-wheel thereon provided with a series of stops, a clutch between the rocker-wheel and cam, and a plurality of detents in position to engage the stops on the rocker-wheel, and a handle on the frame near the operator's position by which said detents are operated, substantially as described.
85. The combination, with the tilt-table and its rocking beam, of the race-cam engaging said beam, the rock-shaft on which said cam is loosely mounted, having a rocker-wheel thereon provided with a series of stops, a clutch between the rocker-wheel and cam, and a plurality of detents in position to engage the stops on the rocker-wheel, and a handle on the frame near the operator's position by which said detents are operated, substantially as described.
90. The combination, with the tilt-table and its rocking beam, of the race-cam engaging said beam, the rock-shaft on which said cam is loosely mounted, having a rocker-wheel thereon provided with a series of stops, a clutch between the rocker-wheel and cam, and a plurality of detents in position to engage the stops on the rocker-wheel, and a handle on the frame near the operator's position by which said detents are operated, substantially as described.
95. The combination, with the rotating carriage having block-receptacles and projections equal in number to the block-receptacles, the rock-shaft having an arm in position for engagement with each of these projections, a spring tending to rock said arm into position for engagement with said projections, and a detent which holds the spring under tension and the arm out of engagement, all combined, substantially as set forth.
100. The combination, with the rotating carriage having block-receptacles and projections equal in number to the block-receptacles, the rock-shaft having an arm in position for engagement with each of these projections, a spring tending to rock said arm into position for engagement with said projections, and a detent which holds the spring under tension and the arm out of engagement, all combined, substantially as set forth.
105. The combination, with the rotating carriage, rock-shaft, and mechanism for throwing the shaft into engagement, as described, of the race-cam on said rock-shaft, a clutch whereby the shaft may be engaged to move the race-cam, and a stop fixed to the frame and engaging said race-cam to hold it (and the tilt-table) in fixed position at the extreme of movement of the table, substantially as described.
110. The combination, with the tilt-table and its oscillating beam, of the rock-shaft and race-cam thereon engaging said beam, the rocker-wheel, a catch on said wheel in position to engage the race-cam, and a pawl on the frame in position to engage the race-cam and to be lifted by the incline on the rocker-wheel, substantially as described.
115. The combination, with the tilt-table and its oscillating beam, of the rock-shaft and race-cam thereon engaging said beam, the rocker-wheel, a catch on said wheel in position to engage the race-cam, and a pawl on the frame in position to engage the race-cam and to be lifted by the incline on the rocker-wheel, substantially as described.
120. The combination, with the tilt-table and its walking-beam, the race-cam engaging said beam, and the clutch-pawl and connecting mechanism, substantially as described, by which the race-cam is actuated from the rock-shaft, of a detent for operating the clutch-pawl the first time and having engagement with the race-cam for causing a second engagement of the clutch-pawl, substantially as set forth.
125. In a shingle-sawing machine, and in combination, a horizontal saw, a rotating carriage having block-receptacles, a tilt-table mounted on universal bearing beneath said

- carrier, mechanism for tilting said table in lateral direction, and a bearing on the frame against which a portion of the table is carried to produce a limited swing of the table in longitudinal direction.
19. The combination, with a rotating carriage and horizontal saw, of a tilt-table having automatic adjustment in all lateral directions, substantially as described.
- 10 20. The combination, with a rotary carriage and horizontal saws, of a tilt-table and mechanism for tilting the same, a rigid pendulous attachment to the tilt-table, and a bearing-surface on the frame, whereby the pendulum may be swung out of true, as set forth.
- 15 21. The combination, with a rotary carriage and horizontal saws, of a tilt-table having a rigid pendulous attachment, an adjustable piece on said attachment, and an adjustable bearing on the frame, against which said pendulum is supported.
- 20 22. The tilt-table supported on wedges having grooves on their lower surfaces, the inverted cups having splines entering said grooves, and the screw-collars and movable risers entering said cups, all the specified elements combined, substantially as stated.
- 25 23. The tilt-table guided by a universal bearing, a pendulum-lever fixed to the table and passing through said bearing, and an adjustable incline on said pendulum engaging a projection on the frame, all the specified elements in combination with mechanism for tilting the table, substantially as described.
- 30 24. The combination, with the frame and the rotating carriage and the movable piece for operating the tilt, of the operator's table in proximity to said carriage, a hinge connecting said operator's table to the frame, and an indicator on the table to show the position at which the tilt must be shifted.
- 35 25. In a shingle-sawing machine, the combination of a horizontal saw, a rotating carrier, a tilt-table mounted on universal bearing beneath the carrier, mechanism for rocking the tilt-table in lateral direction, and an adjustable bearing on the frame, against which part of the table is carried to produce limited longitudinal oscillation, as set forth.
- 40 26. In a shingle-sawing machine, the combination of the saw, the rotating carriage having bolt-receptacles which move over the saw, a bolt-supporting way consisting of two concentric circular tracks and two movable sections side by side and forming part of said tracks, adapted to be displaced from normal positions under the bolt.
- 45 27. The saw and carriage, substantially as described, the circular guideway, movable sections in and forming part of said guideway, supported on hinged posts, and lever mechanism connected to the posts, whereby the sections may be swung radially in opposite directions, all in combination, substantially as stated.
- 50 28. The combination, with the saw and carriage, arranged substantially as shown, of the circular supporting-way beneath the carriage, two movable sections forming part of said way, supported on hinged posts beneath the carriage, and a rod connecting one hinged post from one side of its pivot to the other post at the other side of its pivot, whereby the movable sections may be expanded radially to the table, but in opposite directions, substantially as described.
- 55 29. The combination, with the rotating carriage and its saw, arranged substantially as shown, of the circular way beneath the carriage, having a movable section, a movable bar outside the rotating carriage and connected to the movable section of the way, and a trip on the carriage adapted to be thrown into position to displace the movable track-section, as set forth.
- 60 30. The rotating carriage and saw, arranged substantially as described, the way beneath the carriage having a movable section, the movable bar outside the carriage connected to the movable section, the trip on the carriage, adapted to be thrown into position to engage the movable bar, and a stop on the frame in position to throw the trip out of operative position, substantially as described.
- 65 31. The combination, with a rotary carriage and a horizontal saw, of a block-supporting way consisting of two tracks, a section of each track in advance of the saw made movable, and a catch on the carriage in position to operate both tracks simultaneously, as set forth.
- 70 32. The combination, with the rotating carriage and a plurality of saws, arranged substantially as described, of a way beneath the carriage, having a plurality of movable sections, and a trip on the carriage, adapted to be moved into position to actuate either movable section of the way, as set forth.
- 75 33. The combination, in a shingle-sawing machine, of a plurality of saws on opposite sides of the machine, a rotating table pivoted between said saws and having bolt-receptacles which move over the saws, a dog for each bolt-receptacle and inclines operating radially of the machine to operate said dogs, tilt-tables for each saw and inclines operating radially to change the same, and a way beneath the carriage, having movable sections arranged to be operated radially, and a pusher on the carriage, all substantially as shown and described.
- 80 34. The two saws arranged on vertical arbors at opposite sides of the machine, substantially as described, combined with the sawdust-spout for one saw, open at its side and covering an arc of the saw, and the sawdust-spout for the other saw, presenting its open end toward said saw, the two spouts uniting and extending to the side of the machine, substantially as described.
- 85 35. The combination, with a shingle-sawing machine, of a saw-arbor secured in vertical position at one side thereof, a bracket on the floor or support of the machine, a screw-bolt connected to the bearing-box of the saw-arbor and passing through said bracket, and set-nuts

on said bolt in proximity to the bracket, substantially as described.

36. The combination, with a rotary saw, of a sawdust-spout having a movable section in proximity to the saw, substantially as described.

37. In a shingle-sawing machine, the rotating carriage, the tilt-table, adjunctive shifting mechanism, substantially as described, by which the tilt-table may be shifted by the movement of the carriage, a lever to throw said shifting mechanism into action, and a trip connected to the shifter and operating to disengage the same, so that the tilt is automatically restored to its first position, as set forth.

38. The combination, with the vertical saw-arbor having fixed collars, of a box fitting said collars and adjustable in a bridge-pot, and mechanism for holding said box and the arbor from rising.

39. The vertical saw-arbor and its fixed rings, the box fitting said rings, inclosed in a bridge-pot, a fork crossing said box above the rings, and mechanism for pressing down the fork, substantially as described.

40. The combination, with the vertical saw-arbor having fixed rings, of a box fitting said rings, a bridge-pot in which said box is adjustably inclosed, a fork crossing the dash-pot and bearing down the arbor-box, and a screw by which said fork may be depressed.

41. The combination, with the rotating carriage, of a fixed gage supported on the frame, by which the time for changing the position of the tilt-table is indicated.

42. The combination, with the rotating carriage, a plurality of tilt-tables, and a plurality of saws, of a series of gages supported on the

frame for indicating the time to operate each tilt-table, substantially as described.

43. The combination, with the saw-carriage, of a wooden block furnishing a bearing for the same and an oil-retaining trough in which said block is seated.

44. The combination, with the rotary saw-carriage, of lubricating-blocks supporting the rim of said carriage, a retaining-trough for each block, and an oil-cup communicating with the lower portion of the block, substantially as stated.

45. In combination, in a shingle-sawing machine, a series of block-receptacles grouped round a central axis, a movable dog at the outer side of each block-receptacle, a fixed dog at the inside of each block-receptacle, and an arm connected to the movable dog and extending inward past the fixed dog.

46. The combination, with a rotary carriage and horizontal saws, of a tilt-table having a simultaneous transverse and longitudinal movement, substantially as described.

47. In a shingle-sawing machine, a tilt-table, a carriage, and intermediate adjunctive mechanism by which the tilt-table is shifted by the carriage movement, a catch holding the table in its tilted position, and an abutting surface in position to disengage said catch, so that the tilt-table will be automatically restored to position, substantially as described.

In testimony whereof I affix my signature in presence of two witnesses.

WILLIS J. PERKINS.
